UNITED STATES PATENT OFFICE.

WALTER J. RANDOLPH, OF EMINENCE, MISSOURI.

FIRE-ALARM.

No. 862,199.

Specification of Letters Patent.

Patented Aug. 6, 1907.

Application filed May 4, 1906. Serial No. 315,207.

To all whom it may concern:

Be it known that I, WALTER J. RANDOLPH, a citizen of the United States, residing at Eminence, in the county of Shannon and State of Missouri, have invented certain new and useful Improvements in Fire-Alarms, of which the following is a specification.

The object of this invention is to provide an improved fire alarm mechanism which is so constructed as to automatically sound both a central and a local alarm should a fire break out in any part of the building.

The invention also has for its object to provide an alarm mechanism of this character which is entirely reliable in its operation, being so designed as to be entirely dependent upon the action of weights which are normally held in a raised position by means of the tension in cords of a combustible nature which are strung around the ceiling and flues in such a manner as to be readily severed in case of fire.

For a full description of the invention and the merits thereof and also to acquire a knowledge of the details of construction of the means for effecting the result, reference is to be had to the following description and accompanying drawings, in which:

Figure 1 is a sectional view showing the application of the device; Fig. 2 is an enlarged perspective view of the local alarm mechanism; Fig. 3 is a face view of the central alarm mechanism, the front of the casing being removed; Fig. 4 is a vertical sectional view through the central alarm mechanism; and, Fig. 5 is a detail perspective view showing the manner in which the turning of the reel operates to ring the bell.

Corresponding and like parts are referred to in the following description and indicated in all the views of the drawings by the same reference characters.

In general the device consists essentially of a central alarm mechanism which is operated by a weight, and a series of local alarms which are also operated by weights, the weights being normally held in a raised position by the tension in connecting cord members.

The numeral 1 designates the casing of the central alarm mechanism, the said casing being adapted to be secured to the wall in any suitable position. This casing 1 is provided with a vertical partition 2 between which and one of the sides a reel 3 is journaled. One end of the shaft upon which the reel is mounted extends through the side of the casing 1 and terminates in a knob or finger piece 4, while the opposite end extends through the vertical partition 2 and is provided with a crank arm 5. A cable 6 is coiled about the reel 5 and has its free end secured to a weight 7 in such a manner that a descent of the weight will unwind the cable and thus turn the reel. It will be observed that the lower end of the vertical partition

2 is reinforced by means of a horizontal partition 8 which is located below the reel 3 and connects the said partition to a side of the casing. Immediately above the reel 3 there is located a rocking plate 9 which is pivotally mounted between the sides of the casing. The outer arm of the rocking plate 9 is provided with a pawl 10 which is adapted to engage with a ratchet wheel 11 upon the reel 3 in such a manner as to prevent the reel from turning under the influence of the weight 7. This pawl 10 may be conveniently formed by securing a strip of metal to the rocking plate 9 and bending one of the ends thereof downwardly. Immediately below the reel 3 there is located an oscillating member 12 which is pivoted between the sides of the casing and which is provided with any conventional type of bell 13. An arm 14 extends upwardly from the oscillating member 12 and engages with the crank 5 in such a manner as to cause the member 12 to vibrate and ring the bell 13 when the reel 3 is turned. This arm 14 is preferably formed with a slot within which the crank 5 operates and in the present instance is shown as formed by bending a piece of wire back upon itself so as to form two spaced arms, the ends of which are secured to the oscillating member 12. The inner or free end of the rocking plate 9 is normally in a raised position so that when a weight is imposed thereon, it is lowered and thereby lifts the outer end so as to throw the pawl 10 out of engagement with the ratchet 11.

The top 15 of the casing 1 is formed with a series of perforations 16 through which a number of flexible cord members 17 are passed. The inner ends of the cord members 17 are connected to weights 18 which are located within the casing 1 and are normally held against the top 15 by means of the tension in the cords. Should one of the cords be in any manner broken or severed, the weight 18 which is attached to its inner end will be dropped upon the free end of the rocking plate 9 and the pawl bearing end of the rocking plate will thus be thrown out of engagement with the ratchet 11 and the reel 3 thus permitted to turn under the influence of the weight 7 and ring the bell 13. In order to cause the weights 18 to always strike against the free end of the rocking plate 9, an inclined partition 19 is provided which serves as a guide and in the present instance deflects the weights toward the rear of the casing.

The cords 17 are strung over the ceiling and around the flues and other dangerous places in such a manner as to form a net work, the said cords being held in position by passing them through guide members such as screw eyes 20 through which they are adapted to slide freely. The opposite ends of the cords 17 are wound around the reels 21 of the local alarm mechanisms and have their extremities provided with weights 22. The reels 21 are mounted between the two arms of an ap-

proximately U-shaped frame 23 and are provided at one end with the cranks 24. One of the arms of the U-shaped frame 23 is extended and the oscillating member 25 to which the bell is attached pivoted thereto. 5 These oscillating members 25 are provided with arms similar to the arms 14 which engage with the cranks 24. In this manner it will be apparent that when the reels 21 are turned, the members 25 will be caused to vibrate and ring the bell. These frames 23 are located in various parts of the building and are preferably secured to the ceiling by means of the cross bar connecting the two arms.

Should one of the cords 17 be broken or severed by fire or other means, the weight 22 to which it is attached 15 will be released so as to sound the local alarm, and the weight 18 to which it is attached will be dropped upon the rocking plate 9 so as to sound the central alarm as has been described. In the practical construction of the alarm, the weights 22 are made somewhat heavier 20 than the weights 18 so as to hold the latter in a raised position against the top 15 of the casing and also to take up any variations in the length of the cord due to moisture in the atmosphere.

Having thus described the invention, what is claimed 25 as new is:

1. In a device of the character described, the combination of separate alarm mechanisms, a weight for operating each of the alarm mechanisms, and a cord connecting the said weights and designed to be severed to release the 30 same and permit of the operation of the alarm mechanisms, one of the weights overbalancing the opposite weight whereby the two are normally held in an inoperative position.
2. In a device of the class described, an alarm mechanism embodying operating weights, means for supporting said weights and operable to release the latter whereby the same may actuate the alarm mechanism, a rocking plate pivoted between its ends, an alarm device, means normally connecting one end of the rocking plate with the alarm device to prevent operation of the latter, and means embodying a deflecting partition for directing the weight above mentioned against the other end of the rocking lever to throw the latter out of cooperation with the alarm device and permit of operation of the said device. 35
3. In a device of the class described, the combination of a casing, an alarm device disposed therein and embodying a lever having an attached bell, a reel having a crank connection with said lever to oscillate the latter, weight means connected with the reel to actuate the same and

operate the bell, a rocking plate pivoted between its ends in the casing and normally operatively connected with the reel to prevent movement of the latter, a weight adapted to fall upon an end of the rocking plate to effect release of the reel, supporting means for the last mentioned weight operable to drop the same, and a partition in the casing arranged to deflect the falling weight to cause the latter to strike the rocking lever and effect actuation of the latter. 55

4. In a device of the character described, the combination of a support, a reel journaled in the support, a crank carried by the reel, an oscillating member mounted upon the support, a sounding device operated by the oscillating member, a slotted member carried by the oscillating member and formed by doubling a length of wire upon itself, the said slotted member having an operative connection 60 with the crank arm, and means for turning the reel to sound the alarm. 65

5. In a device of the character described, the combination of a support in the nature of a U-shaped bracket, one of the arms of which is extended, a reel mounted between the two arms of the bracket, a crank carried by the reel, an oscillating member mounted upon the extended arm of the support, a sounding device operated by the oscillating member, means carried by the oscillating member for producing an operative connection with the crank, and 70 means for operating the reel to sound the alarm. 75

6. In a device of the character described, the combination of a support, a reel journaled within the support, means for turning the reel, a sounding device, means whereby the sounding device is operated by the reel, a ratchet carried by the reel, a rocking lever mounted upon the support, a pawl carried by one arm of the rocking lever and engaging the ratchet, a weight, and means for supporting the weight over the opposite arm of the rocking lever. 80

7. In a device of the character described, the combination of a support, a reel journaled within the support, a weighted cord operating the reel, a crank carried by the reel, an oscillating member, a sounding device operated by the oscillating member, a slotted member carried by the oscillating member and having an operative connection with the crank, a ratchet carried by the reel, a rocking lever mounted over the reel, a pawl carried by one arm of the rocking lever and designed to engage the ratchet, and a weight normally suspended over the opposite arm 90 of the rocking lever and designed to disengage the pawl from the ratchet when allowed to drop upon the said rocking lever. 95

In testimony whereof I affix my signature in presence of two witnesses.
